MANUFACTURING COMPANY, OF ELIZABETH, NEW JERSEY, A CORPORATION OF
NEW JERSEY

NEEDLE-BAR MECHANISM FOR SEWING MACHINES

Application filed March 22, 1928. Serial No. 263,628.

This invention relates to sewing machines, more particularly of the type in which a single loop-taker cooperates with a plurality of needles, and has for an object to secure an improved relative timing between the needles and loop-taker, together with an increased lift or clearance of the lower needle above the work and an increased time period that the lower needle is out of the work, during which time the work is moved a stitch-length by the usual feed-mechanism.

To the attainment of the ends in view, provision is made for the differential actuation of the needles, preferably by providing a plurality of needle-bars, one for each needle, and by actuating the needle-bars by separate link-connections with cranks of different radii on a crank-arm carried by a needle-bar operating rock-shaft. When the needles are at the lower end of the stroke, their eyes stand at different elevations, the eye of the needle more remote from the loop-taker being at the lower elevation. The working centers of the needle-bar operating rock-shaft and the link-connection with the needle-bar carrying the lower needle preferably come substantially into alignment, producing a dwell in the lower needle at the end of its down-stroke.

When the needles rise, the lower needle rises more slowly at first as the loop-taker seizes a loop from the higher needle. The up-motion of the lower needle is then accelerated so that its eye will rise to the proper height to form its loop by the time the looper-beak crosses the space between the needles. The acceleration of the lower needle relative to the other needle is continued after the needle-loops are seized, to hasten the time when the lower needle-point is lifted clear of the work; making it possible to begin the feed of the work at an earlier time and continue it over a longer portion of the cycle than heretofore possible in a multiple-needle, single-looper machine. By the time the needles reach the end of the their up-stroke, the accelerated motion of the lower needle has carried it to the same height as the other needle; giving a maximum clearance between the needle-points and the work and enabling the machine

to sew work of maximum thickness. On the down-stroke of the needles, the lower needle descends more rapidly than the other needle and reaches the looper in time to properly enter the looper-thread loop.

In the accompanying drawings, Fig. 1 is a front end elevation of the bracket-arm and cylinder-bed of a sewing machine embodying the invention; the needles being down. Fig. 2 is a similar view with the needles up. Fig. 3 is a view of the needles and looper at the time the latter is seizing a loop from the first needle. Fig. 4 is a section on the line 4-4, Fig. 1. Fig. 5 is a section on the line 5-5, Fig. 1. Fig. 6 is a section on the line 6-6, Fig. 1. Fig. 7 is a side elevation of the parts shown in Fig. 1. Fig. 8 is a top plan view of the needle-bar actuating mechanism. Fig. 9 is a perspective view of the needle-bar operating crank. Figs. 10 and 11 are perspective views of the two needle-bars, disassembled, and Fig. 12 is a diagrammatic view showing the relative differential movements of the needles.

In the preferred embodiment of the invention illustrated, 1 represents the head at the free end of the usual overhanging bracket-arm 2 of a sewing machine, below which bracket-arm is located the cylinder-bed 3. Journaled within and lengthwise of the bracket-arm is the needle-bar operating rock-shaft 4 driven by any suitable mechanism such, for example, as that disclosed in the patent to Gatchell, No. 1,319,469 of October 21, 1919, which also discloses suitable mechanism for operating the sliding and rocking looper-shaft 5 carrying the looper 6.

Journaled in bearings 7 in the head 1 is the needle-bar 8 carrying the needle 9. The needle-bar 8 is formed in one side with a groove 10, Fig. 10, in which is slidably fitted a second needle-bar 11 carrying the needle 12. Clamped to the needle-bar 8 is the split sleeve 13 to which is fixed the stud-pin 14 embraced by one end of a link 15 connected at its opposite end to the crank-pin 16 on the arm 17 fixed to the rock-shaft 4. Secured to the needle-bar 11 by means of the screw 18 is the sleeve 19 to which is fixed the stud-pin 20 embraced by one end of a link 21 con-

nected at its opposite end to a crank-pin 22 carried by the arm 17 and offset from the crank 16.

The crank-pin 22 which actuates the needle-bar 11 carrying the lower needle 12 is set at a greater distance from the axis of the shaft 4 than the crank-pin 16, and the said crank-pins subtend an angle α , Fig. 2, of about 12° . When the needle-bars are down, the crank-pin 22 moves substantially to a point in alignment with the axes of the shaft 4 and stud-pin 20, whereby a dwell is imparted to the lower needle 12.

When the needles are down, the needle 12 stands lower than the needle 9 but need not stand as low as in prior machines where both needles are fixed to the same needle-bar. During the early part of the up-stroke of the needles, the needle 9 rises more rapidly than the needle 12 and reaches the position shown in Fig. 3 in time for its loop to be seized by the beak of the advancing looper 6. By the time the looper beak has crossed the space between the needles, the lower needle 12 has risen to the proper height for formation of its loop for seizure by the looper. Both needles rise at substantially the same speed as the looper is crossing the space between the needles and their difference in elevation during this time is substantially constant.

After the looper has seized the needle-loops, the up-motion of the needle 12 relative to the needle 9 is accelerated to hasten the time that the needle 12 is lifted clear of the work for the work-feeding operation. This acceleration of the up-motion of the needle 12 relative to the needle 9 is continued until the needles reach the limit of their up-stroke, at which time the needle-points stand at substantially the same elevation above the work. This provision secures a maximum time for the accomplishment of the feed of the work and enables the machine to sew work of maximum thickness with a minimum needle-bar stroke.

Having thus set forth the nature of the invention, what I claim herein is:—

1. In a sewing machine, the combination with a loop-taker, and a plurality of needle-bars each carrying a needle, of a needle-bar operating rock-shaft, a plurality of cranks on said rock-shaft, and a link-connection between each of said cranks and a respective one of said needle-bars; the radii of said cranks forming an acute angle.

2. In a sewing machine, the combination with a loop-taker, and a plurality of needle-bars each carrying a needle, of a needle-bar operating rock-shaft, a plurality of cranks on said rock-shaft, and a link-connection between each of said cranks and a respective one of said needle-bars; the radii of said cranks forming an acute angle and being of different lengths, the longer crank being con-

nected to drive the needle which is last passed by the advancing loop-taker.

3. In a sewing machine, the combination with a plurality of needles, a plurality of needle-bars each carrying one of said needles, and a loop-taker for seizing thread-loops from said needles, of a needle-bar operating rock-shaft, a plurality of cranks on said rock-shaft, and a link-connection between each of said cranks and a respective one of said needle-bars, said cranks and link-connections being arranged to move the needle-bars simultaneously in the same direction but at different speeds.

In testimony whereof, I have signed my name to this specification.

GEORGE S. GATCHELL.
